UNITED STATES PATENT OFFICE.

WILLIAM F. FOLMER, OF ROCHESTER, NEW YORK, ASSIGNOR TO EASTMAN KODAK COMPANY, OF ROCHESTER, NEW YORK, A CORPORATION OF NEW YORK.

PHOTOGRAPHIC-PRINTING APPARATUS.

1,378,101.

Specification of Letters Patent. Patented May 17, 1921.

Application filed September 20, 1918. Serial No. 254,926.

To all whom it may concern:

Be it known that I, WILLIAM F. FOLMER, a citizen of the United States, residing at Rochester, in the county of Monroe and State of New York, have invented certain new and useful Improvements in Photographic-Printing Apparatus; and I do hereby declare the following to be a full, clear, and exact description of the same, reference being had to the accompanying drawings, forming a part of this specification, and to the reference-numerals marked thereon.

My invention has for its object to provide an improved apparatus adapted to make two or more photographic impressions upon a single strip of sensitized material, and particularly adapted to printing rapidly and accurately identification cards or passes containing a photograph of the bearer. It is the custom at the present time to admit to establishments in which operations connected with the military branch of service are conducted, only such persons as produce an identification pass containing the photograph of the holder, and owing to the variety of such establishments and to the changing personnel, it is desirable that the identification passes be produced rapidly, uniformly and accurately, as required. In a copending application Serial No. 254,925, filed September 20, 1918, now matured into Patent No. 1,324,887 of Dec. 16, 1919, I have described a camera particularly adapted for taking photographs, which contain, in addition to the portrait of the bearer, further personal designation, such as his height measured and photographically recorded, and his number, a plurality of these photographs being taken upon a strip of negative film, and the present apparatus is designed particularly for printing a complete article, such as a pass containing not only the identifying portrait, but other data or matter relating to the particular plant or establishment in which the pass is to be used. The preferred embodiment of the invention is shown in the drawings, and the novel features will be pointed out in the following specification and claims.

50 In the drawings:

Figure 1 is a plan view of a printing apparatus embodying my improvements.

Fig. 2 is a front elevation showing in sections the containers for the paper upon which the prints are made,

Fig. 3 is a sectional view on the line $x-x$ of Fig. 1,

Fig. 4 is a plan view of the portion of the bed containing the mask and negative used in printing,

Fig. 5 is a vertical section on the line $y-y$ of Fig. 1,

Fig. 6 is a vertical sectional view on the line $z-z$ of Fig. 1, showing the locking device for the presser board,

Fig. 7 is a horizontal section taken on the line $w-w$ of Fig. 6,

Fig. 8 is an enlarged sectional view of the punching apparatus,

Fig. 9 is a vertical sectional view showing the press board taken on the line $v-v$ of Fig. 1, and

Fig. 10 is a view of the character, pass or print made by this apparatus.

Similar reference numerals in the several views indicate the same parts.

1 indicates a table or supporting frame mounted upon the legs 2 and having at opposite ends receptacles 3 and 4 adapted to contain rolls or reels of the photographic paper or other sensitized material on which the prints are to be made. The paper 50 is contained in the roll 5, when unexposed, and, after exposure, is wound on the roll 6. A guideway formed in the present instance by the side strips 17 extends between the rolls, and at a point intermediate the two, the table 1 is provided with an opening 7 covered by a sheet of glass 8 which forms the top of a light box or chamber 9 containing suitable electric lamps or other sources of light. The lamp 10 is preferably a red or non-actinic color, and it is glowing at all times, being arranged permanently in an electric circuit, while the lamp 11 gives preferably white light, and is employed for light printing, and is in an electric circuit embodying conductors 12 and controlled by a switch 13 having a movable plunger 14, the arrangement being such that when the plunger 14 is depressed, the lamp 11 will be lighted. Arranged between the lamps and the transparent support 8 is a diffusing plate 15 preferably of ground or opal glass. The strip guideway between receptacles 3 and 4 and the glass support 8 is covered by strips of relatively soft material 16, such as felt, which is not liable to scratch the sensitized surface of the paper, said strips also extending into the boxes 3 and 4, as shown par-

ticularly in Fig. 1. The guideway for the sensitized paper is formed by the overhanging guide strips 17 at the sides of the support 8, and at the end adjacent the box or receptacle 3, there is a bridge piece or guide 18, as shown in Fig. 8, carrying a strip marker in the form of a perforating punch of any suitable description adapted to form a perforation in the paper before it reaches the printing point, as will be described. In the present instance this punch consists of a suitable plunger 19 retracted by a spring 20, the upper end of the plunger being adapted to be actuated by an arm 21 secured to a member 22 pivoted on brackets 23 and carrying on its under side the felt-covered presser 24, as shown particularly in Figs. 3 and 9, said member 22 having at the front end an operating handle or knob 25. This operating handle is secured to a rod or pin 26 passing through the end of the member 22 and adapted to engage the plunger 14 of the electric switch. Attached to the lower side of the knob or handle 25 is a plate 27 having at one side a segmental slot 28 through which passes a securing screw 29 admitting limited rotary movement of the knob and plate, the other end of the plate extending downwardly beyond the member 22 and having a notch 30 forming a catch adapted, when the member 22 is pressed down and the knob is turned, to engage a plate 31 on the top of the table and hold or lock the member 22 and the presser board, with the paper held tightly in printing contact with the negative or negatives, as shown particularly in Figs. 6 and 7. 35, 35 indicate brackets secured to the front and rear of the table, and supporting spindles provided with operating knobs 36, upon which are spools containing a negative strip 37, said strip extending through apertures in the guide strips 17 (see Fig. 5), across the opening 58 in the bed or table, so that by the manipulation of the knobs, the separating negatives thereon may be brought successfully over the sensitized material extending between the boxes 3 and 4. The negative strip 37 contains the portraits of the prospective bearers of the passes to be printed and such other personal identifying data as desired, as for instance, his height and his designating number (see Fig. 10). Arranged over the opening in the table top and preferably resting directly upon the glass support 8 is a mask 38 having an opening 58, through which light may pass upwardly to the negatives and through it to the paper, and also having a smaller aperture 39 constituting an indicator employed for registration purposes. 40 indicates a negative, also arranged in the guideway for the paper and preferably removably mounted upon the transparent support 8 at one side of the mask 38. This negative con-

tains the legend to be printed upon the sensitized material, such as the name and location of the factory, or other indicia, and also contains an opaque masking portion 41 corresponding in size with and covering the portrait printed through the opening 58 in the mask 38. The portrait negative printed through the opening 58 in the mask and the negative 40 containing the printed matter, are complementary to each other by reason of the fact that the print first made is masked during the second printing operation. The registration mark made by the marker 19 and the indicator 39 are so arranged relative to the printing negatives and to each other that the prints will always appear in proper relation.

The printing apparatus, when in use, is located either in the ordinary dark room, where only the ruby light is used, or where the light is more or less subdued, so as not to fog the sensitized paper. The electric current is switched on illuminating the ruby lamp 10 only. The mask 38 and negative 40 are arranged in position on the transparent support 8, and the negative strip is extended transversely of the support to bring the first portrait negative over the opening 58, the registration of the negative with the aperture in the mask being secured by the light from the ruby lamp 10. The sensitized paper 50 is extended from the receptacle 3 to the receptacle 4, passing over the mask and negatives, and being sufficiently translucent, the outlines of the negatives are visible when illuminated from below. The member 22 is now turned down, pressing the paper in contact with the mask and negatives and is locked by turning the handle 25 to engage the catch plate; the plunger 14 of the switch 13 being operated admits current to the white lamp 11, causing the portrait on the negative strip to be printed on the paper. The movement of member 22 operates the punch 19 through the arm 21, forming a perforation in the paper under the bridge 18. The first print made by the negative 40 contains no portrait. After sufficient time has elapsed to properly print from the negatives, the operator raises the member 22 and feeds the paper 50 forward until the hole formed by the punch 19 is over the aperture 39 in the mask 38, this latter being visible through the paper. The negative strip is now fed to bring the next portrait in alignment with the aperture 58 in the mask, which can also be determined by reason of the translucency of the paper. The punch 19, the mask 38 and the opaque portion 41 of the negative 40 are arranged in such relationship that the portion of the paper on which the portrait is printed will not be doubly exposed. By printing the portrait through a mask, as shown, the print is isolated, and the negative for printing the

body of the pass may therefore contain matter or a legend, above or beneath or in close proximity to the portrait, as, for instance, the date of expiration of the pass, 5 which should be observed by the gateman when comparing the portrait with the person presenting it.

This apparatus is found in practice to be admirably adapted for the purpose, as an 10 unskilled operator may rapidly print a large number of passes in a very short time. The prints may be developed and fixed in long strips or rolls, or if desired, the prints may be separated as soon as made, a groove 55 15 being formed in the table 1 for the passage of the blade of a shears or a knife.

Having described my invention, what I claim and desire to secure by Letters Patent is:

20 1. In a photographic printing apparatus, the combination with a guide for a sensitized strip and a printing negative arranged therein, of a movable presser for holding the strip and negative in printing contact, a 25 marker adapted to act upon the strip and controlled by the movement of the presser, and an indicator with which the mark made on the strip is adapted to coöperate to indicate the feed of the strip.

30 2. In a photographic printing apparatus, the combination with a guide for a sensitized strip, and a plurality of complementary printing negatives arranged therein, of a movable presser for holding the strip in 35 printing contact with the negatives, a marker adapted to act upon the strip and controlled by the movement of the presser, and an indicator with which the mark upon the strip is adapted to coöperate to indicate 40 proper registration of the prints.

3. In a photographic printing apparatus, the combination with a guide for a sensitized strip, a stationary printing negative in the guide and means for guiding a 45 negative strip transversely of the first mentioned guide, of a movable presser for holding the sensitized strip in contact with the negatives, a marker adapted to act upon the sensitized strip and controlled by the move-

ment of the presser, and an indicator with 50 which the mark on the strip is adapted to coöperate to indicate proper registration.

4. In a photographic printing apparatus, the combination with a strip guideway, a plurality of complementary printing negatives arranged therein, an illuminant and a 55 presser for the strip and negatives controlling the illuminant, of a marking punch for perforating the strip and actuated by the presser and an indicator with which the 60 punch mark coöperates.

5. The combination with a strip guideway having a light chamber at one side and adapted to contain a plurality of complementary printing negatives, of a presser on 65 the opposite side of the guideway for holding the strip and negatives in printing contact, a perforating marker actuated by the presser and perforating the positive strip in advance of the first negative and an indicator adapted to coöperate with the perforation thus formed.

6. The combination with a strip guideway having a chamber containing an illuminant, 70 a negative guideway extending transversely 75 of the former, and a movable presser arranged over the guideways, of a strip marker, an indicator with which the marks on the strip are adapted to coöperate, and a switch controlling the illuminant, said 80 switch and marker being operable by the movement of the presser.

7. In a photographic printing apparatus, the combination with a strip guideway having a transparent negative support at the 85 bottom, strip winding reels and a guideway extending transversely of the one first mentioned, of a movable presser arranged at the intersection of the guideways, two illuminants beneath the negative support, 90 one shedding non-actinic and the other actinic light, a switch controlling the actinic illuminant, a strip perforating marker, said switch and marker being operated to mark the strip by the movement of the presser, 95 and an indicator with which the perforations in the strip are adapted to coöperate.

WILLIAM F. FOLMER.
